Kitchell M. Boornan INVENTOR

BY
Howard Greenman
his ATTORNEY

UNITED STATES PATENT OFFICE.

KITCHELL M. BOORMAN, OF NEW YORK, N. Y.

CONTAINER.

Application filed April 30, 1924. Serial No. 709,978.

To all whom it may concern:

Be it known that I, KITCHELL M. BOORMAN, a citizen of the United States, residing at New York city, county of New York, 5 borough of Manhattan, and State of New York, have invented new and useful Improvements in Containers, of which the following is a full, clear, and exact specification.

10 My invention relates to containers and refers particularly to containers suitable for use with toilet preparations.

15 The advantages of containers capable of carrying a plurality of toilet preparations, such as powder compacts, powder puffs, lip sticks, eyebrow pencils, mirrors, &c. is evident and their use and employment has become general.

20 Devices of this character must be strong and firm, in order that the fragile contents may not be broken, and hence, it is customary to make them of metal and particularly of brass composition.

25 Containers of brass and metal construction have the disadvantage of being easily scratched and marked, particularly because they are usually carried in bags with other articles and their beauty and appearance is entirely, or at least partially, destroyed.

30 As all of the toilet preparations are replaceable, the container is used for a considerable length of time, and hence, is subjected to considerable wear.

35 The device of my invention overcomes these objectionable features and presents a container in which the metal parts are protected from wear.

40 My device comprises a flexible cover, containing and enclosing the metal toilet preparation carrier, while maintaining the rigidity of construction necessary for the proper protection of the articles.

45 As my flexible cover can be made of leather, cloth, or other similar material, it allows of wide and extended artistic appearances and thus adds materially to the attractiveness of the container, which can not be obtained in the employment of metal.

50 The construction of my device allows of the convenient use of the toilet preparations with easy replacement of the articles as they are consumed.

55 In the accompanying drawings illustrating modifications of my device, similar parts are designated by similar numerals.

Figure 1 is a perspective view of one form of my device in closed position.

Figure 2 is a plan view of the device of Figure 1 in extended open position.

Figure 3 is a top view of the toilet preparation carrier of Figure 1, removed from the cover and without the toilet preparation articles.

Figure 4 is a section through the line 4—4 of Figure 2, the device being partially open.

Figure 5 is a plan view of a modified form of my toilet preparation carrier.

Figure 6 is a cross-section through the line 6—6 of Figure 5.

The particular form of the device of my invention, shown in Figures 1, 2, 3 and 4 of the accompanying drawings, comprises a flexible container cover composed of a one-piece bottom 10 and top 11. A flexible member 12 is sewed around its two sides and bottom to the top piece 11 as indicated at 13, 13, 13 and intermediate as indicated at 14. A cut-out 15 forms a pocket 16 between the member 12 and the top 11. The space between the sewing lines 13, 14, 13 forms 80 a compartment 17 for the insertion of a mirror 18 which shows through a cut-out portion 19 of the member 12. The extremity of the top 11 is extended into the end piece 20.

85 A compartment capable of receiving a toilet preparation carrier is formed upon the bottom 10 by means of the member 21 connected to the bottom 10 by the sides 22, 22 and the end 23. A pair of projecting male members 24, 24, carried by the end 23 are capable of insertion within a pair of female members 25, 25 carried by the end 20 to maintain the container cover in closed position, as shown in Figure 1. The member 21 has two annular cut-outs 26, 27 and an elongated cut-out 28.

90 The container cover, therefore, comprises a bottom 10 carrying a compartment having three openings in the upper face thereof, the bottom being extended into a top having a pocket compartment and a mirror carrying compartment, the top being capable of placement over and removable attachment to the bottom member.

95 The toilet preparation carrier comprises the bottom 29 extended upwardly into four sides 30, 30 and having a top member 31, in which there are four openings 32, 33 and 34, these openings being so positioned that they

will align with the openings 26, 28 and 27 respectively of the flexible container cover.

Placeable within the opening 32 is a cup 35 carrying the powder compact 36 and the 5 powder puff 37, the flange 38 of the cup resting upon the top 31.

Placeable within the opening 33 is a cup 39 carrying the lip stick 40, the flange 41 of the cup resting upon the top 31.

10 Placeable within the opening 34 is a cup 42 carrying the powder compact 43 and the powder puff 44, the flange 45 of the cup resting upon the top 31.

15 As each of the above-mentioned cups is larger than the corresponding opening in the container cover, the latter holds the cups from accidental displacement.

20 The modification of the toilet preparation carrier shown in Figures 5 and 6 comprises a stamped-out form of device having the bottom 46 the sides 47, 47 and the top 48, the top having the recesses or depressions 49, 50 and 51 capable of receiving a powder compact, a lip stick and a powder puff respectively, these devices being cemented, or 25 glued, therein.

30 From the above it will be seen that my device comprises a leather, or other flexible, container cover having a compartment there- in for a removable toilet preparation carrier, the preparations being capable of use without removal of the carrier, the container cover having also a compartment for a removable mirror capable of use without removal from the cover.

35 I do not limit myself to the particular size, shape, number, material, or arrangement of parts, as shown and described, as these are given simply as a means for de- 40 scribing the device of my invention.

What I claim is:—

1. In a container, in combination, a flexible cover having a bottom portion and a top

portion, the top portion being capable of being folded over and upon the bottom portion, a compartment carried by the inner face of the bottom portion having a plurality of exposed openings therein, a removable toilet preparation carrier within the bottom compartment having a plurality of openings 45 in its upper face corresponding to the openings of the cover and a receptacle carrying cup within each carrier opening.

2. In a container, in combination, a flexible cover having a bottom portion and a top 50 portion, the top portion being capable of being folded over and upon the bottom portion, a compartment carried by the inner face of the bottom portion having a plurality of exposed openings therein, a removable 55 toilet preparation carrier within the bottom compartment having a plurality of openings in its upper face corresponding to the openings of the cover, and a receptacle carrying cup within each carrier opening, the openings of the cups being of smaller dimensions than the openings of the cover.

3. In a container, in combination, a flexible cover having a bottom portion and a top 60 portion, the top portion being capable of being folded over and upon the bottom portion, a compartment carried by the inner face of the bottom portion having a plurality of exposed openings therein, a removable 65 toilet preparation carrier within the bottom compartment having a plurality of openings in its upper face corresponding to the openings of the cover, a receptacle carrying cup within each carrier opening, and a mirror carrying compartment carried on the inner 70 face of the top portion of the cover.

75 Signed at New York city in the county of New York and State of New York this 29th day of April, 1924.

KITCHELL M. BOORMAN.
